UNITED STATES PATENT OFFICE.

GEORGE HAKE, OF ST. LOUIS, MISSOURI; ANNA HAKE ADMINISTRATRIX OF SAID
GEORGE H. HAKE, DECEASED.

DESIGN FOR A HAIRPIN.

57,645.

Specification for Design. Patented Apr. 26, 1921.

Application filed July 29, 1918. Serial No. 247,344. Term of patent 14 years.

To all whom it may concern:

Be it known that I, GEORGE HAKE, a citizen of the United States of America, and a resident of the city of St. Louis, State of Missouri, have invented a new, original, and ornamental Design for Hairpins, of which the following is a specification, reference being had to the accompanying drawing, forming part thereof.

Fig. II is a side elevation of the hairpin shown in Fig. I.

I claim:

The ornamental design for a hairpin, as shown.

In testimony that I claim the foregoing I hereunto affix my signature.

GEORGE HAKE.
